UNITED STATES PATENT OFFICE.

WILLIAM J. MILLER AND DAVID W. JONES, OF COLUMBUS, OHIO, ASSIGNEES OF ONE-
THIRD TO JULIUS F. STONE, OF COLUMBUS, OHIO.

EXPLOSION-ENGINE.

1,104,438.

Specification of Letters Patent.

Patented July 21, 1914.

Application filed March 27, 1909, Serial No. 486,195. Renewed April 6, 1912. Serial No. 689,043.

To all whom it may concern:

Be it known that we, WILLIAM J. MILLER and DAVID W. JONES, citizens of the United States, residing at Columbus, in the county of Franklin and State of Ohio, have invented certain new and useful Improvements in Explosion-Engines, of which the following is a specification.

Our invention relates to improvements in explosion engines and has especial reference to the construction of a valve therefor; our valve is adapted to provide both inlet and exhaust for one cylinder or a plurality of cylinders, and is particularly adapted for use with two cylinders, although its adaptation to four cylinders is readily accomplished. Our improved valve admits the charge longitudinally thereof through an opening approximately at the central point of the circumference of the valve into the cylinder, and the exhaust gases are adapted to be admitted into a longitudinal passageway in the valve and they are exhausted out through the end thereof; the exhaust passage is partially surrounded by the inner end of the intake passage or chamber and the walls are thereby somewhat cooled. Our valve is intended primarily to be rotated, and a device for this purpose is shown in the drawings. The valve is particularly adapted for use with four-cycle engines.

The description of the parts and their combinations will hereinafter be set forth in detail.

In the drawings which are hereto attached and hereby made a part of this specification, Figure 1 shows a vertical transverse section through the cylinders and the valve in place; Fig. 2 shows a longitudinal section through the valve and the actuating means therefor.

Referring to the drawings, 1 indicates a cylinder of an explosion engine, 2 indicates a companion cylinder, and it may be here stated that our valve is primarily adapted for use with two cylinders, although its use is not confined to such construction; 3 is the piston in cylinder 1, and a similar piston 3^a is adapted for actuation in cylinder 2. The valve 4 is preferably mounted in ball bearings 5 to rotate freely, being actuated through the gearing shown at 6; the intake passage 7 is comparatively long and the explosive mixture is admitted thereto through the tube 8. Packing rings are shown at 9, and the gear 10 mounted on the intake

chamber or portion of the valve meshes with the gear 6 for the purpose of giving the valve a rotary movement. The explosive mixture entering through passageway 7 longitudinally of the valve strikes the walls 11 and 12 which form the inner end of the intake passageway and the mixture is thereby directed through the passageway 13 into the explosion chamber of the cylinder.

The timing of the parts being appropriately performed, the explosion will take place and the exhaust gases will thereupon rush outwardly through the passageway 14 into the exhaust passageway 15 and thence into the tube 16 into the outer atmosphere if desired. It will be noted that the walls 11 and 12 forming the inner end of the intake compartment or chamber, project necessarily into the path of the discharge of the exhaust gases, and are thereby heated; the incoming charge, coming into contact with these walls, exercises a cooling effect thereon, and keeps the valve constantly in good working order. Further, the intake and exhaust compartments or passageways through the valve are entirely distinct and separate, which is of importance and which is accomplished by admitting the explosive mixture longitudinally through one end of the valve and exhausting the burnt gases longitudinally through the opposite end of the valve. This valve is seen to be hollow with a partition therein, the ends of the valve being open to communicate with the hollow interior; there are no end walls, and this construction permits free and unobstructed inflow of the combustible mixture and outflow of the exhaust gases. The exhaust does not therefore come into contact with the intake end of the valve, but is confined entirely to the portion of the valve beyond the middle thereof; this makes the valve construction simple and the bearings at the exhaust end only are in danger of heating. The bearings for the intake end of the valve are not subjected to the heat of the exhaust and therefore the problem of mounting the valve is rendered easy. It is seen that the intake and the exhaust are not carried on side by side except in the region of the partition, and this is peculiarly constructed in a manner hereinafter specially described for the purpose of directing the cooling incoming charge against the partition walls which are heated by the exhaust.

Fig. 1 especially shows the adaptation of the valve to two cylinders in which the cylinder ports are shown at 17 and 18; the admission of the combustible mixture from the 5 valve to the cylinders is accomplished through openings 19 and 20 in the valve, which are, as here shown, arranged on opposite sides thereof; the exhaust gases from the cylinder enter the ports 21 and 22 and pass 10 through the passageways 13 and 14 into the main exhaust passage way 15, and so out through pipe 16.

The partition walls 11 and 12 are arranged transversely of the valve as appears in Fig. 15 2, and the partition thus formed is angular in outline, whereby the cool incoming charge is directed over a comparatively large surface heated by the exhaust gases, whereby the walls are beneficially cooled 20 and the exhaust therefore is deprived of some of its heat before passing the region of the bearings. This transverse angular partition wall has advantages which a longitudinal wall does not possess, in that it effectually 25 confines the exhaust at one end of the valve and the intake to the opposite end of the valve, and makes the valve simpler in construction. In this construction of valve, a supply of combustible mixture is 30 always ready to be provided to the cylinders, and the exhaust flows with regularity and uniformity, and the operation of the engine is thereby rendered harmonious and highly efficient. As seen, the valve ports through 35 which the intake is introduced into the cylinder are distinct from those by which the exhaust is permitted to escape, so that we avoid the loss of combustible mixture arising from using the same port for both purposes; further, the arrangement of the passageways within the valve is such that the incoming charge exercises a cooling effect 40 upon the walls of the exhaust passageway, thereby adding to the ease of operation and

the efficiency of the valve. Further, the 45 construction of this valve is such that it is peculiarly adapted for use with two cylinders, supplying the same with charges at appropriate intervals and conducting the exhaust therefrom with certainty and regularity. We are aware that rotary valves are in use, but do not know of any valve which is 50 constructed to admit the charge and to permit the escape of the exhaust in a manner in which we accomplish these functions, and at 55 the same time adapting the valve to a plurality of cylinders. We are aware that a series of valves have been provided for a series of cylinders, but we do not claim such constructions.

We do not limit ourselves to the specific construction herein set forth, but desire to claim any modifications which lie within the scope of our invention.

What we claim is:

In an explosion engine, a cylinder, a rotary valve thereon having open ends and a longitudinal intake passage way communicating with one end, and a longitudinal exhaust passage way communicating with the other 70 end, a partition comprising converging walls interposed transversely in said valve between the inner ends of said passage ways and projecting into said exhaust passage way, said valve having a plurality of openings affording communication between said cylinder and said intake passage way, and a plurality of openings affording communication between said cylinder and said exhaust passage way.

In testimony whereof we affix our signatures in the presence of two witnesses.

WILLIAM J. MILLER.
DAVID W. JONES.
